Primary Examiner — Philip S Hyder

(74) Attorney, Agent, or Firm — Bachman and LaPointe
 PC; George Coury(57) **CLAIM**The ornamental design for a self-cleaning head shape, as
 described and shown.**DESCRIPTION**FIG. 1 is a perspective view of an instrument showing the
 ornamental design of a self-cleaning head shape accordance
 with the invention;FIG. 2 is an enlarged view of the illustration of FIG. 1;
 FIG. 3 is a perspective view of the design of FIG. 1, rotated
 90° around a longitudinal axis of the device;FIG. 4 is a perspective view of the design of FIG. 1, rotated
 180° around a longitudinal axis of the device;FIG. 5 is an enlarged view of the illustration of FIG. 4;
 FIG. 6 is a perspective view of the design of FIG. 1, rotated
 270° around a longitudinal axis of the device; and,FIG. 7 is an end view showing the ornamental design of FIG.
 1.The broken line illustrations in FIGS. 1-7 illustrate environmental
 structure which forms no part of the ornamental
 design of the present invention.**1 Claim, 7 Drawing Sheets**(56)
